UNITED STATES PATENT OFFICE.

GEORGE HARLOW, OF ALTRINCHAM, ENGLAND, ASSIGNOR TO WESTINGHOUSE ELECTRIC AND MANUFACTURING COMPANY, A CORPORATION OF PENNSYLVANIA.

TRANSFORMER.

1,311,507.

Specification of Letters Patent. Patented July 29, 1919.

Application filed June 20, 1916. Serial No. 104,794.

To all whom it may concern:

Be it known that I, GEORGE HARLOW, a subject of the King of Great Britain, and a resident of Woodgarth, Oldfield Road, 5 Altrincham, in the county of Chester, England, have invented a new and useful Improvement in Transformers, of which the following is a specification.

My invention relates to electrical transformers and particularly to core-type transformers in which the coils that constitute the windings are braced to resist permanent displacement resulting from any axial stresses that may be imposed upon them. 10 In core-type transformers, it is usual to wind the low-tension winding into a single coil for each core leg and to dispose this coil closely adjacent to the iron core. The high-tension winding is usually wound into a 15 number of coils which are placed outside of the low-tension coils and arranged coaxially therewith. These high-tension coils, being superposed upon one another, are spaced from one another by means of insulating blocks or insulating washers. If a 20 short circuit occurs on the low-tension side of the transformer, in addition to the very heavy radial stresses set up between the windings, axial stresses are generated which 25 tend to force the high-tension coils apart. Of course, axial stresses are imposed upon the low-tension coils which may be distorted also, but usually are not because of their 30 form of construction. In order to secure the coils against axial movement and to resist the axial stresses that result from short 35 circuits, it has been usual to provide heavy clamps at the top and bottom of the core member to brace the coils against forces 40 that may permanently displace them. It is found, however, that, although these clamps may be forced tightly against the coils when the transformer is built, the coils gradually 45 become loosened after the transformer has been placed in service because of the shrinkage of the insulating material. When the high-tension winding is composed of a large 50 number of superimposed coils, this defect is especially noticeable.

According to the present invention, I provide means whereby the coils may be se-

curely clamped under all conditions and which automatically compensates for any slackness resulting from the shrinkage of the insulating material. My clamping 55 means permits the coils to be axially moved when subjected to axial stresses that, under ordinary conditions, would be dangerous to them. After the axial stresses have subsided, the coils are returned to their original 60 position and firmly held in alinement. Moreover, any axial movement that the coils may partake of is damped in such manner as to preclude them from being suddenly pulled apart. 65

For a better understanding of the nature and scope of my invention, reference may be had to the following description and the accompanying drawing in which Figure 1 is a sectional view of the upper part of a core-type transformer embodying a form of my invention, and Fig. 2 is a similar view of a modified form of the structure shown in Fig. 1.

Referring to the figures, a core leg 1 of 75 a core-type transformer is embraced by a low-tension winding 2 which, in this instance, consists of a single coil for each core leg, and a high-tension winding which consists of a number of superposed coils 3. The 80 low-tension winding 2 is spaced from the core leg 1 by means of an insulating barrier 4 and is separated from the high-tension coils 3 by means of an insulating barrier 5. Each coil 3 is provided with a suitable insulating covering 6 which usually consists of a wrapping of impregnated tape or other insulating material. 85

In Fig. 1, the core member of the transformer is provided with two angle pieces 7 and 8 which are connected by a bolt 9 to clamp the yoke or top portion of the core member. Each of the angle pieces 7 and 8 is provided with a bolt 10 that is engaged by a lock nut 11. The shank of the bolt 10 90 projects into an opening provided in a head member 12. On top of the uppermost high-tension coil 3 is placed a plurality of insulating washers 13 and a steel ring 14 which is slit in any suitable manner to prevent the 95 circulation of eddy currents therein. Interposed between the head 12 and the steel ring 100

14 is a spacing member 15 upon which is formed a flanged portion 16 that is aligned with the head 12. A compression spring 17 is interposed between the flanged portion 5 of the head 12 and a flanged portion 16 of the spacing member 15. The spacing member 15 is provided also with an upwardly extending portion 18 that projects into, and forms a piston member to coöperate with, a 10 downwardly-extending cylinder 19 that is formed integrally with the head member 12. The piston member 18 and the cylinder 19 constitute a dash pot which is surrounded by the compression spring 17. Holes 20, 15 formed in the upper walls of the dash pot, provide means for regulating the damping effect for which the dash pot is furnished by allowing the oil in which the whole mechanism is immersed to pass into and out of the 20 dash pot cylinders. Of course, it will be understood that the dash pots and compression springs permit the high-tension coils to be axially displaced but their movement is damped which precludes them from being 25 rapidly separated when the transformer is subjected to any abnormal stresses. The springs 17 compensate for the shrinkage in the insulation and, under normal conditions, firmly hold the coils in fixed relationship. 30 Any suitable number of dash pots and springs may be provided, depending upon the size of the transformer coils and the necessity for maintaining a substantially uniform compression upon them.

35 In assembling the transformer, the bolts 10 are tightened up, thereby firmly holding the coils 3 by compressing the spring members 17 and adding a sufficient number of insulating washers 13. The spacing member 15 is so designed as not to affect or restrain the action of the dash pot and, therefore, sufficient room must be provided between the head of the cylinder and the top of the piston member 18. When the insulation shrinks, it is compensated for by the 40 springs 17, but any sudden axial movement of the coils resulting from heavy magnetic stresses will be prevented by means of the dash pots, since the oil contained in the cylinders 19 will be prevented from escaping too quickly from them by reason of the comparatively small diameters of the exit holes 45 20. If the whole transformer is not immersed in oil, the dash pots will have a damping action by reason of the compression of the air contained in the cylinders 19.

In Fig. 2, I have shown the compression springs 17 and the dash pot members 18 and 19 placed intermediate the coils 3. The adjacent coils 3 are separated by the compression springs 17 located between split rings 21 and 22, and are held in place by means of the cylinders 19 which, as mentioned

above, coact with the piston members 18 that, in this instance, are threaded into the 65 upper ring 21. The compression of the springs 17 may be adjusted when the transformer is being assembled by means of the usual clamping means at the top and bottom of the transformer core-members. 70

In the foregoing description, I have shown my invention applied to the high-tension windings only of the transformer, but it will be appreciated that a similar structure may be provided for the low- 75 tension winding.

Although I have shown only one form of my invention, it will be understood that many modifications may be made without departing from the spirit and scope of the 80 appended claims.

I claim as my invention:

1. A transformer comprising a core member, current-carrying coils inductively related thereto, elastic means for normally holding and urging said coils together and means for substantially preventing yielding movement of said elastic means when sudden mechanical stresses are imposed on said coils. 90

2. A transformer comprising a core member, current-carrying coils inductively related thereto, elastic means for normally holding said coils in fixed relationship, and retarding means for substantially preventing yielding movement of said elastic means in a reverse direction from that in which the coils are normally urged, when sudden mechanical stresses are imposed on said coils. 95

3. A transformer comprising a core member, current-carrying coils inductively related thereto, elastic means for normally holding and urging said coils together, and a dash-pot mechanism which, when sudden mechanical stresses are imposed on said coils, substantially prevents yielding movement in a reverse direction from that in which said coils are normally urged. 100

4. A transformer comprising a core member and a plurality of superimposed current-carrying coils that are subjected to magnetic stresses directed in axial directions, yielding members for normally holding the coils in firm engagement with one another but permitting them to move temporarily in axial directions to resist the imposed magnetic stresses, and means for retarding the compressive action of the springs to preclude abrupt separation of the coils. 115

5. A transformer comprising a core member, current-carrying coils therefor that are subjected to axial magnetic stresses, springs held in compression for normally holding the coils in fixed relationship to permit them to move axially when subjected to abnormal 120 stresses, and dash pots enveloped by said

springs for retarding the axial movement of the coils, whereby the motion of a coil in response to a slowly applied force is permitted but the motion occasioned by a suddenly applied force is substantially negatived.

5 In testimony whereof, I have hereunto

subscribed my name this nineteenth day of May, 1916.

GEORGE HARLOW.
